ANNIE L. STEWART, OF SOUTH AUBURN, NEBRASKA.

STOVE-LOCK.

1,268,175.

Specification of Letters Patent.

Patented June 4, 1918.

Application filed April 16, 1917. Serial No. 162,368.

To all whom it may concern:

Be it known that I, ANNIE L. STEWART, a citizen of the United States, residing at South Auburn, in the county of Nemaha and State of Nebraska, have invented certain new and useful Improvements in Stove-Locks, of which the following is a specification:

This invention relates to stoves, and it more specifically relates to a stove lock whereby the door or doors of a stove may be locked.

The primary object of the invention is to provide a lock of this character for preventing access to the interior of the stove by children or other unauthorized persons, and thereby to obviate the danger of fire which so often results from children being left alone in a house or room heated by a stove 20 to the interior of which the children have access.

Another object of the invention is to provide a device of this character which precludes access to the interior of the stove, 25 unless a suitable key or opening device is available.

Other objects and advantages will become apparent to persons who read the following detail description and appended claim in 30 connection with the accompanying drawings in which:

Figure 1 represents a conventional form of heating stove having its top portion broken away;

Fig. 2 is an enlarged fragmental detail view illustrating the inner side of the stove door and a fragment of the wall of the stove, the pivotally mounted locking or chocking bar being shown in full lines in its operative position, and in dotted lines in its inoperative position;

Fig. 3 is a view similar to Fig. 2, the difference consisting in the fact that in Fig. 3 the chocking bar is shown both in full lines 45 and in dotted lines in its inoperative position, while the main locking bar is shown in its locking position in dotted lines, and in its non-locking position in full lines; and,

Fig. 4 is a horizontal sectional view on the line 4—4 of Fig. 1.

Referring more specifically to the mechanism illustrated by these drawings, in which similar reference characters correspond with similar parts throughout the several views, the body of the stove is designated by the reference character 10, the lower door 11,

and the upper door 12. It may be assumed that the lower door is mounted on a portion of the stove which is rectangular in horizontal section, and therefore, that the door 11 is rectilinear; whereas the door 12 is arcuate or concavo convex, as illustrated in Fig. 4. The locking mechanism of the lower door may be assumed to be substantially the same as that of the upper door, and hence, a description of the upper door and its locking mechanism will suffice.

The door 12 is mounted to swing on hinges 13 of ordinary construction, and a knob 14, also of ordinary construction may be employed for opening the door when it is unlocked. On the inner wall of the body 10 is formed or secured by proper means a strap or keeper 15, the intermediate portion of which is spaced apart from the wall 10 to provide an aperture for receiving one end of a main locking bar 16, as illustrated in Fig. 2. The locking bar 16 is normally carried by straps or loops 17 and 18, which straps are formed on or secured to the inner surface of the door, approximately at opposite edges of the latter, and these straps constitute bearings in which the lock-bar 16 is slidable horizontally. A supporting bracket is secured to the inner face of the door and comprises a horizontal shoulder or rest 19 and a vertically disposed flange or keeper 20. Upon the rest 19 is normally seated one end of the chocking bar 21, the other end of said bar being supported by a stud or stub 22, one end of which stud or shaft is secured to the member 21. The door 12 is provided with a horizontal slot 23 through which the stud 22 extends, and the latter is provided with a rectangular key-engaging end 24. A collar 25 is secured on the stud 22 and co-operates with a head 26 for securing the members 16 and 21 in juxtaposed and inseparable relation.

When the parts are in their operative or locking position, as illustrated in Figs. 2 and 4, it is obvious that the locking bar cannot be slid leftward because of the contact of the stud 22 against the left-end wall of the slot 23; and it is also obvious that the locking bar cannot be slid rightward because of the contact of the chocking bar 21 with the strap 17. The door cannot, therefore, be opened until the stud 22 is rotated sufficiently to swing the chocking bar 21 upward out of contact with the strap 17, and this cannot be accomplished by use of the fingers

only, because of the comparatively small leverage, the weight of the chocking bar 21, the friction of this bar on the members 16, 20 and 17, and because of the end 24 being 5 too hot to be manipulated by the fingers of an operator; and therefore, a suitable key or wrench must be employed for rotating the stud 22, swinging the chocking bar upward, and sliding the stud 22 to the right-hand 10 end of the slot 23, so as to cause the left-hand end of the locking bar 16 to clear the wall of the body 10. When the device has been operated as described in the foregoing, the stove door may be opened either by the 15 key on the stud 22, or by ordinary means.

From the foregoing it is seen that I have provided a device which renders it safe for children to be left alone in a house with stoves having fire therein, and that the key 20 or wrench for operating this lock may be placed out of reach of the children and used only by authorized persons.

Although I have shown this device as applied to a heating stove, it is not intended 25 to limit my invention to this specific application; and moreover, I do not limit my invention to the exact details of construction disclosed in these drawings, but various minor changes in detail of construction, 30 proportion and arrangement of parts may

be made within the scope of the appended claim and without sacrificing any of the advantages of my invention.

What I claim as my invention is:

In combination with a part having an 35 opening and a door for closing the said opening, keepers on the inner face of the door near opposite edges thereof, said door having a slot in line with the keepers, a locking bar slidable in the keepers, and having its ends adapted to project and engage the part having the door opening at opposite sides of the latter, a chocking bar, a key-operated stud secured to the chocking bar and journaled in the locking bar and 40 operable in the slot of the door, said chocking bar being engageable with one of the keepers to limit the movement of the locking bar in one direction, the stud limiting the movement of the locking bar in the opposite 45 direction by engaging a closed end of the slot in the door, and a keeper to engage and hold the chocking bar in operative position.

In testimony whereof I affix my signature in presence of two witnesses.

ANNIE L. STEWART.
